UNITED STATES PATENT OFFICE.

FRANK A. BAGLEY, OF OMAHA, NEBRASKA, ASSIGNOR OF ONE-HALF TO
J. P. FINLEY, OF SAME PLACE.

WINDMILL AND PUMP COUPLING.

SPECIFICATION forming part of Letters Patent No. 639,494, dated December 19, 1899.

Application filed September 16, 1899. Serial No. 730,762. (No model.)

To all whom it may concern:

Be it known that I, FRANK A. BAGLEY, a citizen of the United States, residing at Omaha, in the county of Douglas and State of Nebraska, have invented certain new and useful Improvements in Windmill and Pump Couplings; and I do hereby declare the following to be a full, clear, and exact description of the invention, such as will enable others skilled in the art to which it appertains to make and use the same.

The object of this invention is to produce a simple and easily-operated device for connecting and disconnecting the connecting-rod 15 of a windmill or analogous machine with a pump-rod or the like.

The nature of the invention is fully disclosed in the description and claims following, reference being had to the accompanying 20 drawings, in which—

Figure 1 is a front view of a device embodying my invention. Fig. 2 is a side view of the same, Sheet 2. Fig. 3 is a central section of the same. Fig. 4 is a detached view of one 25 of the pawls and a portion of the connecting hand-lever.

Similar letters of reference indicate corresponding parts.

In the drawings, A designates the rod connecting with the crank of a windmill or analogous machine. (Not shown.) B is the upper portion of a pump-rod. The usual practice is to connect these parts by a casting fastened to the connecting-rod and provided with a 30 hole to register with a similar hole in the pump-rod, through which passes a suitable bolt. The construction is such that it is practically impossible to connect the parts while the windmill is in motion, and to do so when 35 the windmill is at rest usually requires the forcible raising of the pump-rod, which naturally descends when released from the windmill. The operation is thus one of some difficulty and requires considerable time. My device enables even a child to connect or disconnect the windmill in a moment, and whether 40 in motion or at rest.

Referring now to the drawings, C is a casting provided with a recess at the upper end 45 to take the lower end of the connecting-rod A, to which it is fastened by suitable bolts D.

This casting is hollow, as indicated in Fig. 3, and forms a guide for a slide E, to the lower end of which is secured the pump-rod by a bolt F. The casting C is provided with lateral extensions C' at the lower end, and to one of these is hinged a hand-lever G. To the lever, above the hinge, is pivoted a pawl H, adapted to engage notches E' at the side of the slide E. In practice, for the sake of 50 greater strength and security, another pawl H' is pivoted to a link G², hinged to the opposite extension of the casting, and engages similar notches on the opposite side of the slide. This pawl connects with a downward 55 extension G' of the lever by a link I, so that an outward throw of the lever disengages both pawls. In Fig. 2 it will be seen that the lower portion of the lever is bifurcated, the parts connecting by a bridge G², so as to embrace both the pawl H and the lug C². The bridge serves also as a stop for the pawl which has a shoulder H², as shown in Fig. 4, whereby it may be disengaged from the notches in the slide. 60

The point of engagement of the pawl H with the slide when in operative position is a little outside a line drawn through the center of the hinge and the pivot of the pawl, and thus the lever when thrown to the position 65 shown in Fig. 1 is automatically locked in position. A lug C³ limits the inward movement of the lever. 70

The slide is preferably provided with lateral extensions E², fitted with set-screws E³, 75 by means of which any lost motion may be taken up, and the downward movement of the housing C with respect to the slide may be accurately adjusted so as to coincide with the engagement of the pawls. 80

It is to be understood that the guide or housing C and the slide E are long enough to remain in engagement even with the connecting-rod A at its highest point and the pump-rod at its lowest—that is to say, with the 95 pawls disengaged the slide still enters the housing, which is free to slide up and down on it. To connect the parts operatively, it is but necessary to throw the lever to the position shown in Fig. 1. The first downstroke 100 of the connecting-rod does not bring the housing clear to the limit of movement on the

slide, but the pump-rod is lifted the greater part of its normal stroke, and as the connecting-rod descends faster than the pump-rod naturally falls the parts reach their final operative position in the course of a few strokes. It is to be noted, further, that by a quick back-and-forth movement of the lever, taking advantage of the slow descent of the pump-rod, the latter may be "jacked up" to the limit 10 of its movement in the housing.

Having thus described my invention, what I claim as new, and desire to secure by Letters Patent, is—

1. A connection for a windmill connecting-rod and a pump-rod, comprising a guide or housing attached to the lower end of the connecting-rod, a slide adapted to move freely therein, and secured to the upper end of the pump-rod, said slide being serrated for the 15 engagement of a pawl, a lever hinged to the housing, and a pawl adapted to engage said slide, and to be thrown in and out of engagement by said lever.

2. A coupling for windmill connecting-rods and pump-rods, comprising a notched slide 20 adapted to connect with the pump-rod, a housing to receive the same loosely, and to connect at the upper end with the connecting-rod, a lever hinged to a lateral extension of 25 the housing, and a pawl pivoted to said lever, and adapted to engage the notches on

35 said slide, substantially as and for the purpose set forth.

3. A windmill and pump-rod coupling, comprising a notched slide adapted to connect securely with the pump-rod, a guide or housing therefor, secured at the upper end to the connecting-rod, and having lateral extensions at or near the lower end, a lever hinged to one of said extensions, a pawl pivoted to said lever, another pawl pivoted to the other extension, both pawls being adapted to engage the notches of the slide, and a link connecting the lever with the opposite pawl, substantially as and for the purpose set forth. 40

4. A windmill and pump-rod coupling, comprising a serrated slide secured to the pump-rod, and having lateral extensions provided with adjusting-screws, a guide or housing therefor secured to the connecting-rod, and 45 having extensions coinciding with said adjusting-screws, a lever hinged to one of said extensions, and a pawl connected with said lever, and adapted to be thrown in or out of engagement with the slide thereby, substantially as and for the purpose set forth. 50

In testimony whereof I affix my signature in presence of two witnesses.

FRANK A. BAGLEY.
